UNITED STATES PATENT OFFICE.

JAMES FAY, OF NEW YORK, N. Y.

DESIGN FOR A FURNITURE-SUPPORT.

SPECIFICATION forming part of Design No. 36,401, dated June 30, 1903.

Application filed May 23, 1903. Serial No. 158,550. Term of patent 14 years.

To all whom it may concern:

Be it known that I, JAMES FAY, a citizen of the United States, residing at New York, in the county and State of New York, have invented a new, original, and ornamental Design for a Furniture-Support, of which the following is a specification, reference being had to the accompanying drawing, forming part thereof.

10 The drawing is a front elevation of a furniture-support, showing my new design.

What I claim as new, and desire to secure by Letters Patent, is—
The ornamental design for a furniture-support, as shown.

JAMES FAY.
